SMOKER'S PIPE

Arthur Koenigsamen, Jamaica, N. Y., assignor to
Henry Leonard & Thomas, Inc., Ozone Park,
New York, N. Y., a corporation of New York

Application May 17, 1941, Serial No. 393,883

4 Claims. (Cl. 131—225)

This invention relates to smokers' pipes.

The primary object of the invention is to generally improve smokers' pipes. More particular objects are to prevent "overturning," while using a screw tenon on the stem; to provide a well for moisture and condensate; to provide trap-tubes at the well to prevent undesired escape of moisture into either the bowl or the bit; to arrange for rapid opening of the well for quick draining of condensate; and to provide for more complete separation of the parts of the pipe for thorough cleaning when desired. Still another object is to provide a well located in the screw tenon of the stem, or a well located in the stem, as when using a transparent plastic for the stem, and in the latter case the well located in the tenon may operate as an extension of the well in the stem, in addition to acting as a convenient large-diameter drainage point for quick drainage of the well.

To the accomplishment of the foregoing and other more particularized objects which will hereinafter appear, my invention consists in the smoker's pipe elements and their relation one to the other, as hereinafter are more particularly described in the specification and sought to be defined in the claims. The specification is accompanied by a drawing in which:

Fig. 1 is a partially sectioned side elevation of a pipe embodying features of my invention;

Fig. 2 is a similar view, but with the stem unscrewed for quick drainage of the well;

Fig. 3 is a horizontal section through the stem taken approximately in the plane of the line 3—3 of Fig. 2;

Fig. 4 is a view similar to Fig. 2, but showing the stem and sleeve pulled out of the shank, preparatory to more thorough cleaning of the pipe;

Fig. 5 shows how the sleeve may be unscrewed from the tenon as a further step in the separation of the parts of the pipe for thorough cleaning; and

Fig. 6 is a fragmentary section drawn to enlarged scale, and showing the sleeve and related parts of the pipe in assembled relation.

Referring to the drawing, the pipe comprises a bowl 12 with a shank 14 which may be formed integrally out of a single piece of wood, in accordance with conventional practice. Shank 14 has a hole 16 receiving a sleeve 18. The exterior of sleeve 18 is smooth, while the interior is threaded, as indicated at 20 in Figs. 2 and 6. The pipe further comprises a stem 22 having a flattened bit 24 at one end, and a tenon 26

(Figs. 2, 3 and 5) at the opposite end. Tenon 26 is threaded to mate with the thread 20 on the inside of sleeve 18. Thus the stem may be assembled with the bowl by simply screwing the parts together, as shown in Fig. 1, or they may be separated by simply unscrewing the same, as shown in Fig. 2. The threads 20 and 26 are preferably made relatively coarse and square, so that the stem may be readily unscrewed without accompanying rotation of sleeve 18, this being frictionally held by its fit in the shank. However, sleeve 18 can be rotated by turning the stem clockwise after the tenon has been screwed all the way into the sleeve, and this provides a very convenient way to cure "overturning," which is something that has always proved troublesome in connection with pipes having a screw tenon.

In order to improve the frictional fit of the sleeve in the shank without necessitating expensive precision work, and in order to maintain the desired fit despite changes in temperature, I prefer to insert a liner between the sleeve and the shank, said liner being preferably made of cork or similar soft resilient material. This, however, is not feasible when using a large-diameter tenon and sleeve, as the hole in the shank may become so large as to greatly weaken it. In accordance with my invention, the sleeve is preferably stepped, it having a small-diameter portion 30 in addition to the large-diameter portion 18, both of these preferably being smooth on the outside. The inner portion of hole 16 is lined with a cork liner 32, this preferably being cemented in place in accordance with known practice. The small-diameter portion 30 of the sleeve is dimensioned to be frictionally received in liner 32, while the large-diameter portion 18 is dimensioned to be received directly in the hole 16. The extension 30 of the sleeve is also useful in strengthening the connection between the stem and the pipe, and in providing a metallic smoke passage which helps cool the smoke.

The stem 22 is preferably hollowed to form a well for the collection of condensate from the smoke, and moisture from the mouth of the smoker. This well is clearly shown at 34 in Fig. 3. The tenon 26 is preferably kept large in diameter so that the hole 36 therethrough may be made large enough in diameter to constitute in effect an extension of the well 34, even though hole 36 is smaller than well 34. The pipe is preferably provided with reentrant tubes or trap-tubes at the ends of the well in order to prevent

the collected moisture from running into the mouth of the smoker at one end, or into the bowl of the pipe at the other end. The reentrant tube 38 projects into well 34 from the bit end of the stem toward the bowl. Another trap-tube 40, best shown in Figs. 2 and 6, is most conveniently formed in the sleeve 18. In the present case, it is formed integrally with the sleeve 18, and projects from the small-diameter portion of the sleeve through the large-diameter portion, or toward the open end. Referring to Fig. 6, it will be seen that the hole 36 in the tenon 26 is substantially larger in diameter than the trap-tube 40, and it is for this reason that the tenon may be considered to be itself a well or an extension of the well 34. Without this difference in diameter, the tube 40 would, of course, not be able to function as a trap-tube.

The sleeve is preferably made of metal, for example aluminum or similar light-weight metal. The small and large diameter portions and the trap tube are all formed out of a single piece of metal by appropriate turning operations in an automatic lathe or screw-machine, or the like.

The tenon 26 is also preferably made of a light-weight metal such as aluminum, and is formed integrally with a larger-diameter plug or extension 42. This plug is tapered somewhat, and may be knurled or otherwise appropriately roughened on its exterior so that it may be permanently secured within the large end of stem 22. The plug and tenon member may, if desired, be provided with an integrally formed flange 44 which definitely limits the extent to which the plug may be driven into the stem, and which acts as an ornamental metallic bead for the finished pipe when the parts are assembled as shown in Fig. 1.

The stem may be molded out of a suitable moldable plastic in a single operation. If desired, a transparent plastic may be used, thus making it possible to see whether the well is clean or dirty. The stem may be colored, yet transparent enough for this purpose.

The bit opening 46 may be formed by a core projecting into the bit end of the stem, and the opening 46 is appropriately tapered. The well 34 and trap-tube 38 as well as the smoke passage 48 through the trap-tube, may all be formed by a core projecting into the large end of the stem, and the parts are appropriately tapered to facilitate removal of the core. After the stem has been molded in one piece, as above explained, it is readily completed by driving the plug and tenon member with a force fit into the open end of the stem.

It is believed that the construction and operation, as well as the many advantages of my improved pipe, will be apparent from the foregoing detailed description thereof. The stem is provided with a screw tenon, yet no special hand-fitting is needed to bring the bit to desired horizontal position, and no difficulty with "overturning" can arise, because the position of the bit may be set at any time, by simply turning the bit to proper position.

The pipe may be taken apart in either of two ways. To hastily drain excess moisture from the well, it is merely necessary to unscrew the stem, thereby opening one end of the well and so permitting the moisture to drain therefrom. The stem may, of course, be shaken to facilitate this operation. This temporary sort of cleaning may be performed several times in the course of a day, as for example, when on the street. The

frictional grip of the shank on the sleeve is greater than the resistance of the stem to unscrewing, and this desired result is enhanced by making the thread a coarse, square thread, and by providing a small-diameter sleeve portion which is received within the resilient cork liner. The large-diameter hole through the tenon facilitates draining the well, and also has the advantage that the tenon may itself act as a part of the well. This in turn has the advantage that the trap-tube at the bowl end of the well may be relatively short, thus facilitating its formation integrally with the sleeve, and without unduly complicating the machine operation needed to form the thread on the inside of the sleeve. For a more thorough cleaning, the stem and sleeve may be pulled out of the shank, as shown in Fig. 4, and the sleeve may then be unscrewed from the tenon, thus separating all the parts so that they may be individually cleaned, and so that a pipe cleaner may be readily run through the various smoke passages.

It will be apparent that while I have shown and described my invention in a preferred form, many changes and modifications may be made in the structure disclosed, without departing from the spirit of the invention as sought to be defined in the following claims.

I claim:

1. A smoker's pipe comprising a bowl with an integral shank having a relatively large-diameter hole, the inner portion of said hole being provided with a liner made of cork or similar soft resilient material cemented in place, a metal sleeve having a smooth exterior including a small-diameter portion and a large-diameter portion, the small-diameter portion being dimensioned to be frictionally received in the cork liner, the large-diameter portion being dimensioned to be received in the outer portion of the hole, the large-diameter portion of the sleeve being internally threaded with a relatively coarse thread, and a stem having a bit end and a male tenon projecting from its opposite end, said tenon being externally threaded to mate with the internal thread of the sleeve, the friction between the sleeve and shank being greater than that of the thread whereby said stem may be separated from the shank by unscrewing the same, but "overturning" may be cured by rotation of the stem and sleeve relative to the shank.

2. A smoker's pipe comprising a bowl with a shank having a relatively large-diameter hole, the inner portion of said hole being provided with a liner made of cork or similar soft resilient material, a sleeve having a smooth exterior with a small-diameter portion and a large-diameter portion, the small-diameter portion being dimensioned to be frictionally received in the cork liner, the large-diameter portion being dimensioned to be received in the outer portion of the hole, the large-diameter portion of the sleeve being internally threaded with a relatively coarse thread and having a trap-tube projecting from the small-diameter portion into the large-diameter portion, and a stem having a bit end and a male tenon projecting from its opposite end, said tenon being externally threaded to mate with the internal thread of the sleeve, said tenon having a hole therethrough which is substantially larger in diameter than the trap-tube of the sleeve in order to form a well for the collection of moisture, the friction between the sleeve and shank being greater than that of the thread, said stem therefore being readily unscrewable to drain moisture.

from the well, said sleeve being removable from the shank for more thorough cleaning, and rotatable to cure "overturning."

3. A smoker's pipe comprising a bowl with a shank having a relatively large-diameter hole, the inner portion of said hole being provided with a liner made of cork or similar soft resilient material, a sleeve having a smooth exterior with a small-diameter portion and a large-diameter portion, the small-diameter portion being dimensioned to be frictionally received in the cork liner, the large-diameter portion being dimensioned to be received in the outer portion of the hole, the large-diameter portion of the sleeve being internally threaded with a relatively coarse thread and having a trap-tube projecting from the small-diameter portion into the large-diameter portion, and a stem having a bit end and a male tenon projecting from its opposite end, said tenon being externally threaded to mate with the internal thread of the sleeve, said tenon having a hole therethrough which is substantially larger in diameter than the trap-tube of the sleeve, in order to form a well, said stem having a trap-tube projecting toward the bowl and into the well, the friction between the sleeve and shank being greater than that of the thread, said stem therefore being readily unscrewable to drain moisture from the well, said sleeve being removable from the shank for more thorough cleaning, and rotatable to cure "overturning."

4. A smoker's pipe comprising a bowl with an integral shank having a relatively large-diameter hole, the inner portion of said hole being provided with a liner made of cork or similar soft resilient material cemented in place, a metal sleeve having a smooth exterior with a small-diameter portion and a large-diameter portion, the small-diameter portion being dimensioned to be frictionally received in the cork liner, the large-diameter portion being dimensioned to be received in the outer portion of the hole, the large-diameter portion of the sleeve being internally threaded with a relatively coarse thread and having a trap-tube projecting from the small-diameter portion through the large-diameter portion, and a stem having a bit end and a male tenon projecting from its opposite end, said tenon being externally threaded to mate with the internal thread of the sleeve, said stem being hollowed to form a well and having a trap-tube projecting toward the bowl and into the well, said tenon having a hole therethrough which is substantially larger in diameter than the trap-tube of the sleeve, whereby said tenon forms a continuation of the well, the friction between the sleeve and shank being greater than that of the thread, said stem being therefore readily unscrewable to drain moisture from the well, and said sleeve being removable from the shank for more thorough cleaning, and rotatable to cure "overturning."

ARTHUR KOENIGSAMEN.
